New Orleans, La.

Application September 8, 1948, Serial No. 148,508

Term of patent 14 years

(Cl. D14—3)

To all whom it may concern:

Be it known that we, Stephen J. Loyacano and Erasmus L. Loyacano, citizens of the United States, residing at New Orleans, in the Parish of Orleans and State of Louisiana, have invented a new, original, and ornamental Design for a Hot Dog Vending Cart, of which the following is a specification, reference being had to the accompanying drawing, forming part thereof.

Figure 1 is a perspective view of a hot dog vending cart, showing our new design,

Figure 2 is a side elevational view thereof, and Figure 3 is a front elevational view of the same.
We claim:

The ornamental design for a hot dog vending cart, as shown.

STEPHEN J. LOYACANO.
ERASMUS L. LOYACANO.
